His Attorney.

UNITED STATES PATENT OFFICE.

EDWARD J. RETZBACH, OF ST. LOUIS, MISSOURI, ASSIGNOR, BY DIRECT AND MESNE ASSIGNMENTS, TO SAID EDWARD J. RETZBACH, TRUSTEE.

ART OF MAKING AND PACKAGING PASTRY.

1,411,223.

Specification of Letters Patent. Patented Mar. 28, 1922.

Application filed June 17, 1921. Serial No. 478,268.

To all whom it may concern:

Be it known that I, EDWARD J. RETZBACH, a citizen of the United States, and residing at St. Louis, Missouri, have invented a new and useful Improvement in the Art of Making and Packaging Pastry, of which the following is a specification.

This invention relates to the art of making and packaging pastry for delivery to the ultimate consumer.

One of the objects of this invention is to evolve a process whereby the pastry is baked in the package in which it is delivered to the ultimate consumer, in such a manner as to simplify the baking operation and deliver the product in convenient and desirable form.

Another object is to provide a merchantable unit in which the baked pastry is enveloped and protected, and whereby it can be readily taken out of the box without breaking the baked pastry.

Further objects will appear from the detail description taken in connection with the accompanying drawing, in which:

Figure 1 is a sectional view of a unit embodying this invention; and

Figure 2 is another view showing the manner in which the box is taken from the baked pastry.

Referring to the accompanying drawing, the box 1 is formed of paper or any other suitable material of that nature; it is, therefore, to be understood that the word "paper" as applied to the material from which the boxes are made, is intended as a word of general description and not of limitation, but to include paper or like non-metallic materials which are commonly used for such purposes. This box is provided with a liner 2, which may be formed of grease-proof or vegetable parchment or any other suitable material adapted for this purpose. This liner is loose in the box and is preferably formed of a single sheet of proper shape and conforming to the inside of the box. This liner is, however, attached to the box along its upper edges only, and preferably by folding the edges of the liner over the edges of the box as shown at 3 and pasting the same along the outside faces of the box along its upper edges. This leaves the liner loose in the box and attached only along its upper edges. The cover 4 for the box may also be formed of paper or any other suitable

material in the usual manner and is also provided with a loose liner or sheet 5 arranged loosely in the cover.

In accordance with this invention the lined box is filled with the pastry and the filled box is then placed in an oven to bake the product in the box. During this baking operation the box is preferably left uncovered so as to permit the product to rise and brown as may be desired; after the product has been baked in the box the cover is placed thereon, thereby forming a merchantable unit. In some cases it may be desirable to cover the box during the baking operation; in such case the cover and its lining is placed on the box and the product is then baked in the filled and covered box.

It will, therefore, be seen that in accordance with this invention there is provided a merchantable unit which is ready for delivery to the ultimate consumer. By baking the product in a lined box not only is this product enveloped by a sanitary envelope, but the baked product can also be removed readily from the box, as the product does not stick to the box either in the baked or unbaked semi-fluid state as is the case where metal and lined metal boxes are used. This removal can be simply accomplished by removing the cover and inverting the box, when it can be raised from the product, the liner peeling off as shown in Figure 2, in view of the fact that this liner is entirely loose from the box except that it is attached thereto along its edges; the product, therefore, remains whole and unbroken.

In view of the fact that the lining engages the box along its edges, filling thereof is facilitated, so that the semi-fluid product does not fall between the box and its lining, which may otherwise cause charring and adhesion as well as improper baking when the box is placed in the oven. It will also be noted that the attachment of the lining is such as to keep the paste securing this lining wholly out of contact with the product enveloped thereby, either directly or indirectly through the lining.

In accordance with this invention, the product is baked in a lined paper box as distinguished from a metal receptacle or lined metal receptacle. In a metal receptacle, the product will not only invariably adhere to the metal enveloping the same, but the baking is also ununiform, as the tendency is for

the outside to become baked rapidly, thereby providing an insulating covering preventing thorough baking of the interior. This difficulty is not overcome by lining a metallic box, because not only is there then a tendency of the lining to become charred, but there is still a tendency to burn the outside or bake it hard, while the inside remains undone. In the lined paper box, however, 10 there is no tendency of the lining to adhere to the box body, nor is there a tendency of the lining to become charred. This is for the reason that the box itself as well as the lining is a poor conductor of heat, and accordingly the baking will be gradual from 15 the outside to the innermost parts of the product enveloped by the lining and by the box. Accordingly there is no tendency of the outside becoming burnt, charred or even 20 overdone but the baking will be uniform throughout, while the exposed top can be properly browned as is desired.

It is obvious that various changes may be made in details without departing from the 25 spirit of this invention; it is, therefore, to be understood that this invention is not to be limited to the specific details shown and described.

Having thus described the invention, what 30 is claimed is:

1. In the art of making and packaging pastry for delivery to the ultimate consumers, the process comprising, filling a lined

paper box with the product, and baking the product while in the filled box, substantially as and for the purpose set forth. 35

2. In the art of making and packaging pastry for delivery to the ultimate consumers, the process comprising, filling a lined paper box with the product, baking the product while in the filled box, and placing the cover on the filled box, substantially as and for the purpose set forth. 40

3. In the art of making and packaging pastry for delivery to the ultimate consumers, the process comprising, filling a paper box with the product placed inside and enveloped by a loose liner attached to the box at its upper edges, and baking the product while in the filled box, substantially as and 45 for the purpose set forth. 50

4. A merchantable unit comprising, a lined paper box enveloping and protecting pastry which has been substantially uniformly baked in the box, substantially as 55 and for the purpose set forth.

5. A merchantable unit comprising, a paper box having a loose liner attached to the box at its upper edges, and enveloping and protecting pastry which has been substantially uniformly baked in the box, substantially as and for the purpose set forth. 60

In testimony whereof I affix my signature this 23rd day of May, 1921.

EDWARD J. RETZBACH.
